(57) **CLAIM**

The ornamental design for a spring-actuated water bottle lid, as shown and described.

DESCRIPTION

FIG. 1 is a perspective view of a spring-actuated water bottle lid, shown in a closed position and attached to a mug environment.

FIG. 2 is a perspective view of the spring-actuated water bottle lid of FIG. 1, shown in an open position and attached to a mug environment.

FIG. 3 is a top view of the spring-actuated water bottle lid of FIG. 1.

FIG. 4 is a front side elevational view of the spring-actuated water bottle lid of FIG. 1, shown in a closed position; and,

FIG. 5 is a rear side elevational view of the spring-actuated water bottle lid of FIG. 1, shown in a closed position.

The broken lines shown in the Figures are for illustrative purposes only and form no part of the claimed invention. The bottom of the spring-actuated water bottle lid is unornamented.
